UNITED STATES PATENT OFFICE

ROBERT K. DOHERTY, OF DETROIT, MICHIGAN, ASSIGNOR TO THE DIEBOLD SAFE & LOCK COMPANY, OF CANTON, OHIO, A CORPORATION OF OHIO

GAS PROTECTED LOCK

Application filed January 11, 1930. Serial No. 420,110.

My invention relates to locks, and more particularly to combination locks including a rotatable spindle for operating the combination mechanism.

Such a lock is usually used for maintaining the door of a chest, safe, or vault in the bolted and locked position, and the combination mechanism is usually mounted in a case which is secured upon the inside of the door, and the spindle extends through a bore in the door and terminates on the outside thereof in a knob and dial.

Unauthorized persons, vandals, or robbers attempting to gain access to the interior of a chest, safe, or vault, the door of which is protected by such a combination lock, usually attempt to hammer off the lock knob and dial, and drive the spindle inwardly, thereby moving the lock tumblers in the case out of line with the dog or fence, and releasing the locking engagement of the bolt stop with the bolt of the lock.

The activities of such unauthorized persons, vandals, or robbers may be rendered ineffective if it is possible to discharge poisonous or disagreeable gases into the zone of unauthorized, destructive, or felonious operations.

The objects of the present improvements include the provision, in a combination lock and the like, of an improved lock spindle including a frangible gas container mounted therein and a knob, so that any hammering on the knob or spindle will break the container and release the contained gases into the atmosphere adjacent the knob and in front of the door upon which the lock is mounted.

These objects are attained in the present invention, as is hereinafter claimed, and a preferred embodiment of which is herein-after set forth in detail.

The preferred embodiment of the invention is illustrated in the accompanying drawings forming part hereof, in which

The figure is a transverse sectional view of a door having mounted thereon one of the improved gas protected locks hereof, the section being taken on the longitudinal axis of the lock spindle.

Similar numerals refer to similar parts in the drawing.

The improved gas protected lock is indicated generally at 10 and includes a lock case 11 in which are operatively mounted 55 a usual mechanism for a combination lock for controlling the extension and withdrawal of the lock bolt 12.

The lock case 11 is mounted in a usual manner on the inside face 13 of a door 14 which 60 may be the door of a money chest, safe, or vault.

The door 14 has a bore 15 formed therein and the bore 15 is preferably provided with 65 a tubular liner 16.

A novel lock operating spindle indicated generally at 17 extends from an operative connection with the lock mechanism within the case 11 through the bore 15 beyond the outside face 18 of the door 14; and the spindle 70 17 terminates at its outer end on the outside of the door, in a control knob 19.

The control knob 19 is preferably secured upon the outer end of a knob shaft 19a comprising one of the parts of the novel spindle 75 indicated generally at 17, and a dial 20 is mounted on the knob shaft 19a for use in a usual manner with a dial index plate 21 mounted on the outside face of the door 14.

The improved spindle indicated generally 80 at 17 when being installed on the door as illustrated, is arranged to be inserted from the outside through the bore 15 into the lock case 11 where connection with the tumblers is made.

The spindle 17 includes an inner shaft 22, one end of which extends within the lock case 11 and connects with the tumblers therein, and the other end 23 of which is located outside the case within the bore 15 and is threaded, as indicated, for screwing into a threaded aperture at the inner end 24 of a longitudinally extending gas container shaft 25.

A key 26 is also located between suitable 95 keyways formed in the threaded aperture of the container shaft 25 and on the inner shaft 22 for insuring rotation of the inner shaft 22 when the container shaft 25 is rotated.

The container shaft 25 may preferably be made from a length of round shafting of a 100

larger diameter than that of the inner shaft 22, and a gas container chamber 27 is formed therein as by counterboring the container shaft 25 from the outer end thereof.

5 The outer end of the container shaft extends into a counterbore 28 which is formed in the inner end of the knob shaft 19a, and the knob shaft 19a and the container shaft 25 are secured to each other by radially extending screws 29 which are screwed into registering threaded apertures in the telescoping container shaft 25 and knob shaft 19a.

10 The container shaft 25 has formed therein intermediate its ends circumferentially extending gas ports 30.

15 Within the bomb chamber 27 of the container shaft 25 a longitudinally extending frangible gas container 31 is located, and the container is preferably in the form of a glass shell within which the poisonous or disagreeable gases are contained.

20 The container 31 has formed therein a neck groove 32 of reduced diameter which is located in alignment with the inner ends of the screws 29; and the inner ends of the screws 29 extend into the neck groove so that displacement or knocking off of the knob shaft 19a by hammering or the like will break the container 31 usually at the neck groove 32, the ends of the screws 29 being impinged against the container at the neck groove.

25 For positioning the shell bomb 31 within the container chamber 27 in a novel manner to make certain the release of the container gases when the lock is attached, the ends of the container are supported in spacer plug supports 33 and 34 which are preferably made of cementitious material, such as rubber cement.

30 The outer end 35 of the container 31 is preferably pointed as indicated, and extends into the outer end plug support 34 whereby a blow on the knob 19 or knob shaft 19a which may not be sufficient to entirely fracture the container at the neck groove, will crack the same intermediate its length due to its beam-like extension in the spacer plug supports 34 and 33.

35 Likewise a direct blow on the end of the knob 19 axially of the spindle, will fracture the container by instantaneously moving the plug support 34 toward the plug support 33.

40 During operations of professional cracksmen, the knob shaft 19a will usually be completely knocked off and the gas from the fractured container 31 will be released directly from the forward end of the container, and will issue forth into the atmosphere in front of the door, thereby driving away or 45 disabling the cracksmen.

45 If, however, the blow is not sufficient to knock off the knob shaft 19a its inner shoulder 36 which normally bears against the outer face of the door 18 will be displaced therefrom and from its usual bearing engagement

with the indicator plate 21, whereby gas will pass through the ports 30 and the bore 15 and the aforesaid openings between the knob shaft and the door formed by displacement of the knob shaft.

70 In this event the atmosphere in front of the door will likewise be filled with the poisonous or disagreeable gases.

75 The container illustrated is preferably made of glass but may be made of any desired frangible material.

I claim:

1. A lock including an operating spindle extending therefrom, supporting means on the spindle, a frangible gas container carried by the supporting means, there being a neck groove formed in the container, and members extending from the spindle into the neck groove.

80 2. A lock including an operating spindle extending therefrom, supporting members on the spindle, a frangible gas container interposed between and having its ends mounted in the supporting members, there being a neck groove formed in the container, and members extending from the spindle into the neck groove.

85 3. Operating means for a lock, said operating means being adapted to hold a frangible gas container and comprising a spindle, a knob secured to said spindle, and means for rigidly securing spaced portions of said frangible container to said knob and said spindle whereby relative displacement between said knob and said spindle will cause 90 said frangible container to break.

95 4. Operating means for a lock, said operating means being adapted to hold a frangible gas container and comprising a spindle extending from said lock, said spindle being 100 provided with a chamber holding one end of said frangible container, a knob secured to said spindle and provided with a chamber for holding the other end of said frangible container, and means for rigidly securing said 105 ends of said frangible container to said knob and said spindle to insure the breaking thereof when said knob is displaced relative to said spindle.

110 5. Operating means for a lock adapted to hold a frangible gas container having a restricted portion intermediate its ends, said operating means comprising a spindle having a chamber formed therein to receive one end of said frangible container, a knob having a chamber therein for receiving the other end of said frangible container, and means for securing said knob to said spindle and adapted to break said frangible container portion 115 from said restricted portion when said knob is displaced relative to said spindle.

120 6. Operating means for a lock, said operating means being adapted to hold a frangible gas container and comprising a spindle extending from said lock, said spindle being 125

provided with a chamber holding one end of said frangible container, said spindle having holes therein through which gas may be discharged from said chamber, a knob secured to said spindle and provided with a chamber for holding the other end of said frangible container, and means for rigidly securing said ends of said frangible container to said knob and said frangible container will fracture when said knob is displaced relative to said spindle.

6 7. Operating means for a lock, said operating means being adapted to hold a frangible gas container and comprising a spindle extending from said lock, a knob secured to said spindle, and cement securing one end of said container to said knob and the other end of said container to said spindle so that said container will fracture when said knob is displaced relative to said spindle.

15 8. In operating means for a lock, a spindle extending from the lock, a sealed frangible container carried by said spindle, said container being adapted to hold a quantity of 25 gas, and a knob secured to said spindle and adapted to fracture said container when it is displaced relative to said spindle.

20 9. In operating means for a lock, a hollow spindle extending from the lock, a sealed frangible container disposed in said spindle, said container being adapted to hold a quantity of 25 gas, and a knob secured to said spindle and adapted to fracture said container when it is displaced relative to said spindle.

35 10. In operating means for a lock, a hollow spindle extending from the lock, a sealed glass container mounted in said spindle, said container being adapted to hold a quantity of gas, and a knob secured to said spindle and adapted to fracture said container when it is displaced relative to said spindle.

40 In testimony that I claim the above, I have hereunto subscribed my name.

ROBERT K. DOHERTY.
